UNITED STATES PATENT OFFICE.

ROGER POTTER AND HENRY McDougall, OF NEW YORK, N. Y.

SWITCH FOR SUSPENDED RAILWAYS.

SPECIFICATION forming part of Letters Patent No. 367,842, dated August 9, 1887.

Application filed April 4, 1887. Serial No. 233,680. (No model.)

To all whom it may concern:

Be it known that we, ROGER POTTER and HENRY McDougall, both citizens of the United States of America, and residents of the 5 city, county, and State of New York, have invented a new and useful Improvement in Switches for Suspended Railways, of which the following is a specification.

This invention relates to an improvement in 10 switches for suspended railways, such as are used for carrying and transferring meat or other weights; and it consists in the construction and combination, with the suspended main rail and its chair or hanger, of a dropping and 15 vertical diagonal-jointed switch-rail for switching from the main rail, by which means a very simple and more solid and less expensive switch is obtained than with those heretofore used.

20 In the drawings hereto annexed, Figure 1 represents a side view of a portion of a suspended railway with several switches from a main to branch railways constructed according to our invention. Fig. 2 is a top view of 25 the same, showing the several branch railways connecting with the main railway. The chairs or hangers are shown bisected. Fig. 3 is a side view of one of the railway chairs or hangers. Fig. 4 is a horizontal section of the pivoted 30 switch-rail joint.

A represents a main rail, and B B are branch rails, which connect with the main rail by means of the switch-rails C, and the meat carrier or car D is fitted to travel upon said rails, 35 and may be switched to either of them. The rails are suspended on the ceiling of the room or building by means of railway chairs or hangers E, secured to the ceiling. At the junction of the main railway with one or more 40 branch railways each railway is provided with a switch-rail, C, of which the proper rail for passing the meat-carrier is dropped to connect with the main, and those not engaged may be raised by hand and held up out of the 45 way by spring-hooks H, hereinafter referred to, to pass by the meat-carrier. The main rail end F at such junction is supported and attached to the side of a hanger, E, and the switch-rails meet the main with a diagonal 50 joint, the pointed ends of the switch-rails being fitted to join the main between the side of

the hanger and the point at the end of the main rail. The opposite ends of the switch-rails are each pivoted to its respective rail and meet with a vertical diagonal joint, through 55 which the pivot G passes at right angles to said joint, and said pivot is riveted in a counter-bore made in each opposite end of the joining-rails, so that the switch-rail can be readily turned on the pivot to raise its loose 60 end from its junction with the main rail; but when dropped to connect with said main rail the switch-rail in such position presents an even surface over its junctions with the main rail, as well as over its pivoted joint, to avoid 65 all obstructions against the smooth travel of the meat-carrier, which object is mainly gained by the employment of the diagonal joints of the switch-rail. The end of the rail close to the pivoted end of the switch-rail is secured 70 to a hanger applied thereto. For holding the switch-rails up out of the way which are not engaged, we employ the spring J, which is secured on the fixed rail or hanger near the pivot-junction of the switch-rail, and said 75 spring has a hooked end, so that its hook H passes under the switch-rail as soon as said rail is raised properly. By this means said rail is held up out of the way for the carrier to pass.

80 Whichever branch rail is desired to be used, the respective switch-rail is readily dropped in its seat to connect with the main rail by disengaging its spring-hook H. The switch-rail not used is held up out of the way by the 85 spring-hook H.

What we claim as our invention, and desire to secure by Letters Patent, is—

1. In a suspended railway, the combination, 90 with the supporting-hangers and the main and branch rails, of the dropping switch-rails C, adapted to connect the main rail with the side rails, and suitable spring-hooks for holding the switch-rails out of engagement with the main rail when not in use, all substantially as 95 and for the purpose specified.

2. The combination, in a suspended railway, 100 of a pivoted switch-rail connected with its main-track rail by a vertical diagonal joint and pivot at right angles to said joint, all substantially as specified.

3. The combination, with the main rails A

and the branch rails B and their supporting hangers, of the switch-rails C, united to their respective rails by diagonal vertical joints and rivets G, and the spring-hooks H, for holding the switch-rails out of engagement with the main-track rail, all constructed and arranged to operate substantially in the manner and for the purpose set forth. In testimony that we claim the foregoing as

our invention we have signed our names, in presence of two witnesses, this 31st day of August, 1886.

ROGER POTTER,
HENRY McDougall.
